UNITED STATES PATENT OFFICE.

CARL H. BISSELL, OF SYRACUSE, NEW YORK, ASSIGNOR TO CROUSE-HINDS COMPANY,
OF SYRACUSE, NEW YORK, A CORPORATION OF NEW YORK.

DESIGN FOR AN ELECTRICAL-CONDUIT OUTLET-BOX.

47,985.

Specification for Design.

Patented Oct. 19, 1915.

Application filed July 19, 1915. Serial No. 40,779. Term of patent 14 years.

To all whom it may concern:

Be it known that I, CARL H. BISSELL, a citizen of the United States, residing at Syracuse, in the county of Onondaga and State of New York, have invented a new, original, and ornamental Design for Electrical-Conduit Outlet-Boxes, of which the following is a specification, reference being had to the accompanying drawing, forming a part hereof.

In the drawing, Figures 1 and 2 are perspective views of this conduit outlet box, Fig. 2 looking downwardly in Fig. 1.

This new design for conduit outlet boxes presents in plan the appearance of a disk *a*, and an elongated bar *b* extending diametrically across the disk on the face thereof, one

end *c* of the bar projecting beyond the periphery of the disk, and the other end *d* being within said periphery, and having an upright tubular extension.

What I claim is:—

The ornamental design for an electrical conduit outlet box substantially as shown and described.

In testimony whereof, I have hereunto signed my name in the presence of the attesting witness, at Syracuse, in the county of Onondaga, and State of New York, this 15th day of July, 1915.

CARL H. BISSELL.

Witness:

Wm. CORNELL BLANDING.
